UNITED STATES PATENT OFFICE.

GEORGE A. ALBRIGHT, OF ATLANTA, GEORGIA.

CLOCK-CIRCUIT-CONTROL DEVICE.

1,416,592.

Specification of Letters Patent. Patented May 16, 1922.

Application filed February 4, 1920. Serial No. 356,314.

To all whom it may concern:

Be it known that I, GEORGE A. ALBRIGHT, a citizen of the United States, and resident of Atlanta, in the county of Fulton and State of Georgia, have invented a new and Improved Clock-Circuit-Control Device, of which the following is a full, clear, and exact description.

This invention relates generally to a circuit control means for electric devices having circuit closers in which it is imperative that a circuit establishing means be provided which is positive and durable in operation. More particularly, this invention relates to a circuit closing means for electric clocks, and a means for enabling a circuit periodically to be completed, and to vary the period through which the circuit is periodically established and maintained.

In the electric clocks heretofore provided, it has been common practice to periodically establish a circuit by means of platinum circuit closers associated with the pendulum and escapement mechanism of the clock.

The circuit for electromagnetic devices controlling the clock winding and striking mechanism, and other secondary clock movements were thus controlled by the periodically actuated platinum circuit closers. It has been found in practice, that the troubles and difficulties of the electric clock installations are primarily due to the unsatisfactory character of the contacts. After a certain period of time troubles and difficulties invariably develop resulting in defective operation caused by the improper functioning of the circuit closing contacts. In electric clocks, the proper functioning of the contacts is necessary, because they are the vital parts of the system upon the proper functioning of which depends the accuracy of the time piece. For instance, one of the difficulties heretofore encountered, due to defective contacts has resulted in what is

known as stepping up, which is caused by rough contacts which cause a succession of impulses through circuits controlling the master clock or secondary circuits.

A further objection to the devices heretofore provided for electric clocks, has been that objectionable noises are produced by the operation of electromagnets. Further, it has not been possible to obtain a dependable circuit closer for introducing a sufficient time period in a circuit for enabling

relatively large masses to be moved, for purposes such for example as for actuating a gong or winding mechanism.

One of the objects of this invention is to provide an improved circuit closing means periodically actuated for establishing a circuit throughout a period, which is simple in construction and positive, durable and reliable in operation, and which will overcome the objections above noted in devices heretofore employed.

A further object of this invention is to provide a method which will enable the time period through which a circuit is energized, to be adjusted and controlled, through an improved circuit closer periodically actuated by a pendulum or other time controlled device. A particular advantage of such an arrangement, is that it will enable the time period of a circuit to be properly controlled to permit relatively large units to function, for example to wind the clock, actuate striking mechanism, or control other secondary circuits.

Still a further object of this invention is to provide in an electric clock a circuit closing means intermittently actuated through a pendulum and escapement mechanism, the circuit closer being of such a type that the area of the parts establishing the circuit is continually changing throughout the period of contact, thus affording a reliable and durable closer, eliminating the cause for defective operation through repeated interruptions of the circuit at any one point.

More specifically, an object of this invention is to provide a circuit closer for a time control device comprising contacts, one of which is movable periodically, as for instance by a pendulum, the other comprising a liquid mercury contact movable intermittently to a position in which the contact, movable periodically by the pendulum movement, is permitted to dip within the mercury cup contact. A particular advantage of a contact of this type, is that substantially no pressure is required to be exerted between the contacts in order to effect a proper closing of the circuit. This feature is of importance in insuring accuracy in delicate instruments.

A further object of this invention is to provide a circuit closer including a mercury contact movable intermittently to engage another contact controlled by a pendulum

movement, to control the circuit of an electroresponsive device, as for instance a reciprocating motor, so that the said motor may be energized throughout a required period 5 in order to permit the winding or striking mechanism of a clock to be directly actuated, as for example through a pawl and ratchet mechanism. The advantage of providing a reciprocating motor functioning 10 through a pawl and ratchet connection, is that objectionable noise is eliminated, and instead of a mechanical cushion being utilized for limiting the movement of the actuating member, a magnetic cushion is 15 formed by the movement of the armature of the motor in a magnetic field. Such a device is applicable for use in small clocks adapted for private use, where quiet and reliable operation is desirable, and is also 20 applicable for use on very large clocks adapted for use out of doors in public places. In the latter use, a device constructed in accordance with this invention will enable the usual counterweights required for the large hand to be dispensed 25 with. Further, a time control circuit of this character may readily be used to control a suitable striking device for large clocks requiring the use of heavy parts.

30 Another more specific object of this invention is to provide in a circuit closer, a mercury cup contact of such a construction as will permit a certain amount of movement and jolting without spilling the liquid.

35 The cup may be so proportioned as to be held in an inverted position and still retain the contents.

An important advantage in providing a circuit closer for a clock including a mercury cup contact, is that the accumulation 40 of dust and dirt will not interfere with the proper functioning of the circuit closer. It has been found by experimenting and testing over a period of time, that the accumulation 45 of dust and dirt particles upon the surface of the liquid contact does not interfere with the operation of the circuit closer. By the provision of a circuit closer including a liquid mercury contact in a master 50 clock, the operation of systems controlled by such a master clock is rendered practically infallible in so far as difficulties due to the collection of dirt upon the contacts is concerned.

55 The invention consists in providing a liquid or mercury cup contact intermittently movable to engage another contact movable periodically with a pendulum whereby a positive and durable contact is afforded 60 throughout a desired period for an electroresponsive control device.

Other objects and advantages will be apparent from the following specification, and the accompanying drawings forming part 65 of this specification, and showing for ex-

ample one practical embodiment of the invention. The invention will be more particularly pointed out in the appended claims.

In the accompanying drawings similar characters of reference designate, corre- 70 sponding parts in the several views.

Figure 1 is a diagrammatic view in elevation, looking in the direction of the arrows and taken on the line 1-1 of Figure 2, showing certain parts broken away, of a 75 clock mechanism embodying the invention, the hands of the clock being shown in dot and dash lines.

Figure 2 is an elevation view partly in section looking in the direction of the arrows 80 and taken generally on the line 2-2 of Figure 1.

Figure 3 is an enlarged view showing more clearly the liquid or mercury contacts.

Figure 4 is an enlarged elevation view 85 partly in section showing the contacts, the method of mounting the same, and a means for adjusting the parts to vary the period of contact.

Figure 5 is a plan view showing a means 90 of adjusting one of the contacts.

With reference more particularly to the accompanying drawings showing for example one practical embodiment, the invention is shown as applied to a clock mechanism well known in the art, and as shown herein comprises a pendulum having a rod 1 and a weight 2 adjustably carried at one end thereof, said pendulum being suspended in a well known manner through a spring 100 member 3 connected to a support 4 which in turn is secured to a suitable standard 5. A suitable frame is shown consisting of front and back plates 6-7 respectively, connected by suitable rods 8, and in which the shafts, 105 hereinafter to be mentioned, are rotatably supported. An escapement mechanism is mounted in the frame, consisting of an escapement wheel 9 mounted on the shaft 10 which is rotatably supported in the plates 110 6-7. A verge 11 mounted on a verge shaft, 12 is also shown rotatably mounted in the plates 6-7, the said verge shaft being connected in a manner well known in the art with the pendulum rod 1 by a member 13, 115 and the verge 11 is arranged to co-operate with the teeth 14 of the escapement wheel in a well known manner. The escapement mechanism is connected through a suitable 120 train of gears with a spring motor mechanism, shown as comprising a spring 15 wound on a suitable drum 16. One end 17 of said spring is connected to a rod 18 secured to a gear 19 which in turn drives a gear 20 mounted on the escapement shaft 125 10, through the intermediate gears 21-22 mounted on a shaft 23 rotatably supported, the said gears 21 and 22 engaging respectively, gears 19 and 20. Preferably the gear ratio between the gears 20 and 19, is sixty 130

to one, so that for one revolution of the gear 20, there will be one sixtieth of a revolution of the gear 19. The other end 24 of the spring 15 is connected to another rod 25 which is connected with a toothed ratchet wheel 26, to turn therewith. The rods 18 and 25 connected respectively with the ends 17 and 24 of the spring, are preferably of such a length and so positioned on the respective gear 19, and ratchet wheel 26, that they will strike each other when the spring is fully wound. In this manner, the rods 18 and 25 act as stops to prevent excess spring tension. It is of course understood that the gear 19, and the ratchet wheel 26, are rotatably mounted in a suitable manner to permit independent movement.

As a means of moving the hour and minute hands 27 and 28 respectively, the movement of the gear 19 may be transmitted through a shaft 29 to the minute hand 28, and through suitable gearing not shown, the hour hand 27 may be actuated by suitable connections well known in the art. It is to be understood that this invention is not to be limited to the arrangement of parts and certain details of construction herein shown, but that the same may be varied to suit individual preference and conditions of use.

30 A means is provided for automatically winding the spring and keeping a practically uniform tension upon the gear 19 through the spring 15. In order to effect this purpose, preferably, a reciprocating motor 30, of suitable construction having an armature 31 is provided to intermittently actuate the ratchet wheel 26, which wheel in turn moves the rod 25 therewith and thus winds the spring 15 a certain amount. In 40 the form shown, the armature 31 may be rotatably mounted in any suitable manner on a shaft 31' between pole pieces 32, 33. A crank arm 34 is shown secured to the shaft 31', and is connected by a link 35 to one 45 end of an arm 36, the other end of said arm being rotatably mounted in a suitable manner upon a shaft 37. A spring pressed pawl 38 is shown pivotally mounted on the arm 36, and one end of said pawl is adapted to 50 engage the teeth of the ratchet wheel 26. It is thus seen that an oscillating movement of the armature 31, will move the arm 36 from a position indicated by the dot and dash line, to the full line position, as indicated in Figure 1, and will accordingly rotate the ratchet wheel 26 a part of a revolution. The spring pressed pawl 38 functions as an actuating pawl to rotate the ratchet wheel 26, and the spring pressed pawl 39 55 functions as a holding pawl. In order to restore the arm 36, and the armature 31 to a normal position, a spring 40 may be provided. It is to be understood, that the ratchet wheel 26 may be provided with any 60 number of teeth, but preferably sixty is employed, a suitable means being provided for intermittently energizing the oscillating motor at minute periods. In this manner, the clock is wound every minute, thus maintaining a relatively constant spring tension. 70 One of the advantages in providing a reciprocating motor for effecting the winding operation, is that objectionable noises are eliminated. In devices heretofore employed, electromagnets have been provided for this 75 purpose, and these have been objectionable for reasons above noted. A further advantage in providing a reciprocating motor, is that a magnetic cushion effect may be utilized to limit the movement of the winding 80 mechanism. Further, by the use of a reciprocating motor, together with the circuit control means hereinafter to be described, relatively large units may be controlled for winding large clocks.

85 As before stated, an inherent weakness of the time clocks heretofore employed, has been the use of circuit closers including a plurality of solid metallic contacts, as for instance of platinum. In order to insure accurate time keeping, it is of utmost importance that there be no chattering of the contacts due to worn parts, or the collection of dust or dirt, for under such conditions, a 90 succession of circuit impulses are formed which result in a "step up" operation. Further one of the reasons that a suitable electric striking device has not been used, and also one of the reasons why the application to large public clock has not been satisfactory, is due to the difficulty of providing a 95 satisfactory means for introducing a suitable time period in energizing a circuit. The inertia difficulties due to relatively heavy parts have made necessary the provision of a suitable time period in which to 100 permit the parts to function. It has been found in practice, that by providing a mercurial contact in the control circuits for the 105 electric clock, that the difficulties heretofore encountered are overcome, enabling a system 110 to be provided which is durable, reliable and practically infallible in operation.

115 In the preferred form shown, a cup 41 having liquid mercury 42 therein, is shown mounted on an arm 43 pivotally supported at 43', the said arm having a counterbalance weight 44 suitably arranged at the other end thereof. The other part of the circuit closer is shown as comprising a contact 45, preferably composed of platinum, the said contact being adjustably connected to another arm 46 mounted on the verge shaft 12 so as to have a continuous periodical movement therewith. In the form shown, the arm 46 120 is mounted on blocks 47, 48 preferably composed of insulating material, and a suitable counter balance weight 49 is provided for the arm 46. It is thus seen that the contact 41 will periodically dip within the liquid 125 130

mercury 42 of the mercurial cup contact, and the contact will continue for a certain period, which may be varied. It is to be noted that when the contact 45 dips within the liquid mercury that the continuous contact is maintained, but that the area of the parts in contact is continually changing. In other words, the contact is maintained throughout a portion of two vibrations of the pendulum.

10 A further advantage of the mercurial contact for such a purpose, is that no appreciable force or pressure is required in effecting the contact, as is necessary when solid contacts are used. This is a feature which

15 further contributes towards accuracy and efficient operation of the electric clocks embodying mercurial contacts.

In order to bring the mercurial contact of the circuit closer into operative position

20 intermittently, a means is provided for moving the arm 43 at the desired time, and for a desired period. In the form shown, for this purpose, a disc 50 is mounted on the escapement shaft 10, and is provided with

25 an arm 51 having a cam face 52 thereon which is adapted to engage a pin 53 mounted on the arm 43, so that intermittently for a desired period, the mercury cup contact is moved to a position in which the contact 45

30 may dip within the liquid mercury. It is to be understood that this invention is not to be limited to the means shown herein for actuating the arm 43, but any other suitable construction may be provided for this purpose.

35 In the form shown, the mercurial contact is connected in the circuit of the reciprocating motor 30, so that at the proper time the said motor will be energized for a desired period and thus automatically wind

40 the spring of the clock. It is to be noted that by providing a suitable arrangement of the mechanism for intermittently actuating the arm 43, that the liquid contact may be brought in a functioning position at any

45 time, and for any desired period. It is further to be understood that other circuit closers of this character may be suitably arranged to control a striking mechanism, or other secondary circuits, in which it is desirous to introduce a certain period for operation, and electrical connections well known in the art may be provided for this purpose.

In operation, the period through which

55 the contact is established may be varied by changing the angular relation of the arm 46 carrying the platinum contact, on the verge shaft, or by varying the design of the mercury cup containing the liquid, so as to permit a relatively deep cup portion to be formed.

60 This would permit the platinum contact 45 to move within the liquid mercury for a substantial period, thus energizing a control circuit for a corresponding period. With

65 reference to Figure 3, showing a mercury cup

in section, it is apparent that the end of the platinum contact 45 may move within the liquid mercury a substantial distance.

With reference to Figures 4 and 5, a modification is there shown in which the mercury cup 41 is adjustably carried on the arm 43, and the contact 45 is shown adjustably carried on the arm 46. Such a construction, permits the period through which the contact is established to be varied without change in the design of the contacts forming the circuit closer. This is effected by moving the respective contacts to different positions on the arms. A set screw 54 is shown as a means for adjusting the arm 46 about the verge shaft 12.

A further feature to be noted is that by providing a cup having a relatively small diameter as compared with the depth, that the mercury is readily retained in the pocket. It has been found in practice, that it is possible to so design the cup portion that the same may be inverted, without the mercury falling therefrom. This is an advantageous feature in a device of this character in which both contacts are movable.

As shown in Figure 1, the motor 30 is connected in series with the mercurial contact circuit closer, and the battery 55 as a source of current supply, but it is to be understood that any suitable source of current supply may be provided. It has been found in practice, that a mercurial contact of this character may be used in a circuit of relatively high voltage. This has not been practicable in the ordinary circuit closers now provided. Such a feature, readily enables a motor of substantial size to be employed for large clocks.

While a certain practical embodiment and modified form have been shown herein, it is to be understood that various changes and modifications may be made without departing from the spirit and scope of this invention.

Having thus described my invention, what I claim as new and desire to secure by Letters Patent, is

1. A time control mechanism comprising a circuit including an electroresponsive device, and a circuit closer comprising a plurality of contacts, one of said contacts being movable with a pendulum, the other contact including a mercury cup being movable intermittently to engage the first named contact.

2. In a time control device a circuit closer comprising a plurality of contacts one of said contacts including a liquid mercury contact periodically actuated by the time control device, the other contact including a member movable periodically with a pendulum and adapted to engage the mercury contact for a given period.

3. In a time control device a circuit closer comprising a plurality of contacts one of

- said contacts including a liquid mercury contact periodically actuated by the time mechanism, the other contact including a member movable periodically with a pendulum and adapted to engage the mercury contact for a given period, whereby the area of the parts is continually changing throughout the period of contact and a means for varying the period of contact.
- 10 4. In a time control device a circuit closer comprising a plurality of contacts one of said contacts including a liquid mercury contact periodically actuated by the time control device, the other contact including a member movable periodically with a pendulum and adapted to engage the mercury contact for a given period, whereby the area of the parts is continually changing throughout the period of contact and a means for varying the maximum area of the parts in contact.
- 15 5. In a time control device a circuit closer comprising a plurality of parts, one of said parts being movable periodically by a pendulum, the other part comprising a mercury
- cup, arranged to contact with said first named part throughout a portion of two beats of the pendulum, whereby a circuit is completed for a determinate period, the area of the parts in contact changing throughout 30 the period for which the contact is maintained.
6. A circuit closer including a mercury contact, and another contact having a periodic movement controlled by a pendulum 35 adapted to engage the mercury contact throughout a portion of two vibrations of the pendulum.
7. An electric circuit control for a time indicating device including means to operate 40 said time indicating device, a pair of electric contacts, one continuously oscillating, and the other periodically actuated and brought into contact with the oscillating contact thereby providing energy for said time device operating means, said periodically actuated contact comprising a mercury cup into which the oscillating contact immerses.

GEORGE A. ALBRIGHT.
